COLLIMATING DEVICE FOR TELESCOPIC SIGHTS OR SIMILAR ARTICLE

Susumu Fukushima, Tokyo, Japan, and Willard H. Korte,
North Miami Beach, Fla., assignors to Tasco Sales,
Inc., Miami, Fla.

Filed Apr. 15, 1971, Ser. No. 134,239

Term of patent 14 years

Int. Cl. D16—06

U.S. Cl. D57—1 E

FIG. 1 is an isometric view of a collimating device for telescopic sights or similar article showing our new design.

FIG. 2 is a rear elevational view thereof.

FIG. 3 is a side elevational view thereof.

The portions of the collimating device not shown are similar to those disclosed.

We claim:

The ornamental design for a collimating device for telescopic sights or similar article, as shown and described.
